UNITED STATES PATENT OFFICE.

FRED D. JORDAN, OF FARMINGTON, MAINE, ASSIGNOR TO EPHRAIM R. HACKETT, OF FARMINGTON, MAINE.

GAS-GENERATOR.

1,319,344.

Specification of Letters Patent.

Patented Oct. 21, 1919.

Application filed July 31, 1916. Serial No. 112,380.

To all whom it may concern:

Be it known that I, FRED D. JORDAN, a citizen of the United States, and resident of Farmington, in the county of Franklin and 5 State of Maine, have invented new and useful Improvements in Gas-Generators for Internal-Combustion Engines, of which the following is a specification.

This invention relates to gas generators 10 for internal combustion engines, and particularly to generators utilizing the heat of the exhaust from the engine for converting kerosene oil into gas.

It has heretofore been proposed to accomplish this by passing the kerosene through a long convoluted coil of pipe in contact with the hot exhaust gases from the engine, but such devices have not proved successful, partly, I believe, on account of the excessive 20 length of single pipe required, partly on account of the tortuous form of the pipe necessitated to bring it within practicable dimensions, and partly on account of the fact that while the volume of the kerosene gas increases by expansion as it progresses 25 through the system the cross-sectional area of the coiled pipe does not also increase and the gas is able to expand only lengthwise of the pipe. But whatever the causes, it 30 has not been found practicable with the devices heretofore used, as far as I am aware, to supply the gas to the engine adequately to meet the varying demands of the motor.

With the present invention instead of 35 passing the kerosene through a long convoluted single coil in the presence of the hot exhaust gases, I pass the fuel through one or more groups of small pipes in parallel, the several groups, where more than one group 40 is used, being preferably arranged in series and being preferably of progressively increasing cross-sectional capacity. This makes it possible to secure as great or greater heating surfaces for the gas forming pipes 45 as with a single coil pipe, but accomplishes the result without convolutions which tend to impede the flow of the gas. It also makes it possible to increase the combined cross-sectional area of the pipes to accommodate 50 their expanding contents, without increasing the diameter of any individual pipe, which would sacrifice its quick heating quality. And by using more than one such group of pipes it makes it possible to progressively 55 increase successive groups of the series in

cross-sectional capacity. These and other features of the invention will hereinafter be more fully described and particularly pointed out in the claims.

In the accompanying drawings which 60 illustrate one embodiment of the invention,

Figure 1 is a plan view of a generator containing the invention attached to an ordinary four-cylinder internal combustion engine;

Fig. 2 is a vertical section partly in elevation, showing the interior of the generator;

Fig. 3 is a horizontal section on line 3—3 of Fig. 2;

Fig. 4 is a vertical section on line 4—4 of Fig. 2; and

Fig. 5 is an enlarged detail in vertical longitudinal section through the mixing chamber and the gas delivery nozzle.

A represents the casing of an ordinary four-cylinder internal combustion engine having a pair of gas intake ports *a*, *a*, each supplying two cylinders, and four exhaust ports *b*, *b*, *b*, *b*, one from each cylinder.

The outer casing 1 of the generator is secured to the cylinder casing A by a series of bolts 2 passing through casing 1 and into the casing A. The casing 1 is relatively long and slender to fit alongside of the engine casing A, and is provided with a series of exhaust inlet ports 3, 3, 3, 3, which register with the several exhaust ports *b* of the engine casing, and a pair of outlet ports 4, 4, which register with the gas intake ports *a*, *a*, 90 of the engine. The several registering ports are suitably sealed to form gas-tight joints.

The exhaust inlet ports 3 open into a heater chamber 5, which extends throughout the length of the casing and occupies the major portion thereof. The heater chamber 5 is divided by a lengthwise partition 6 from the exhaust discharge passage 7, which extends alongside the heater chamber 5 and prevents loss of heat by radiation 100 through the partition 6 near which one of the groups of gas-forming pipes is located. The exhaust gases from the engine entering the ports 3 pass through chamber 5 to the outlet port 8 at one end, connecting the chamber 5 with the discharge passage 7, and thence the gases pass through passage 7 alongside of the heater chamber to the outlet 9.

A mixing chamber or manifold 10, curved 110

around the two middle ports 3, connects the two ports 4 which are joined to the intake ports *a*, *a* of the engine.

An air intake casing 11, having a spring-pressed air supply valve 12 and a control valve 13, is secured to the middle part of the mixing chamber 10. In operation suction from the engine created within the mixing chamber 10 draws in valve 12 acting through duct 15, compressing the spring 14 and thereby opening passage 15 to the atmosphere. The passage 16 is controlled by valve 13 which is fixed to a rotatable stem 17 journaled in the casing 11.

Kerosene is introduced from a suitable tank or other source of supply (not shown) through the fuel supply pipe 20, which enters the heater chamber 5 at the same end as the discharge port 8 of the heater chamber. Immediately inside of the outer wall of the casing the kerosene pipe branches or is divided into a plurality of smaller pipes 21 (four being here shown) arranged in a group in parallel and spaced apart sufficiently to allow free circulation about them of the hot exhaust gases. The pipes 21, which are preferably straight, extend substantially the length of the heater chamber along one side near the wall 6 and unite again at the opposite end in a common header 22.

Another group of small pipes 23, similarly arranged in parallel and suitably spaced apart, extend from header 22 to another common header 24 at the end of the heater chamber opposite the header 22. The group of pipes 23 are preferably larger in number than the group of pipes 21, thus affording a larger combined cross-sectional area to provide for the increasing volume of the expanding gases due to the heat as the gases progress through the system.

The individual pipes of each group are arranged in parallel with each other, and are preferably also substantially geometrically parallel, but the two groups are in series one with the other.

From the header 24 a gas delivery pipe 25 leads back to the middle part of the casing and there bends and enters the mixing chamber 10, terminating in a discharge nozzle 26, over which is a concave cap or shell 27 arranged to deflect the gases laterally in either direction into the mixing chamber 10, as indicated by broken lines in Fig. 5.

The kerosene is vaporized or converted into gas during its passage through the groups of pipes 21 and 23 by the heat of the exhaust from the engine within the heater chamber 5. The gas is mixed with air in chamber 10 and thence delivered through ports 4, 4, to the cylinders of the engine. The explosive mixture in chamber 10 is also kept hot by the heater chamber

5 and the discharge passage 7, which adjoin and partly inclose the chamber 10, the discharge passage 7 constituting an auxiliary heating chamber.

To start the engine before the generator 70 has been sufficiently heated to vaporize the kerosene, the kerosene supply is cut off by a suitable cock (not shown) in pipe 20, preferably located within convenient reach of the operator, and an auxiliary or starting supply pipe 28 (Fig. 2) which connects with an auxiliary or starting gasoline supply is opened. The gasoline and air mixture is then supplied through mixing chamber 10 to the cylinders of the engine, and 80 the engine is run just long enough on this mixture to warm up the heater chamber 5, whereupon the gasoline supply is cut off and the kerosene supply is opened through pipe 20 and the engine will continue to operate on the kerosene gas mixture.

The gas supply through pipe 25 is controlled by a valve 30 which is rotated by stem 31. The gas valve 30 and the air control valve 13 may be operated in unison in 90 any usual or convenient manner by means of levers and connecting rods controlled from the operator's station and connected to the valve stems 31 and 17.

By having the fuel supply pipe enter the 95 heater chamber 5 at the end where the discharge opening 8 is located the gas generating pipes 21 and 23 which extend the whole length of the chamber and back again are brought into contact with all the heated exhaust gases before the gases escape through outlet pipe 8, thus utilizing the heat to the full extent.

I claim:

1. A gas generator for internal combustion engines comprising a casing having a series of exhaust inlet ports adapted for connection to the exhaust ports of the engine, and outlet ports adapted for connection to the gas intake ports of the engine, a heater chamber in said casing into which said exhaust inlet ports open, and a separate mixing chamber in the casing from which said outlet ports open, a fuel supply pipe entering the heater chamber, a gas delivery pipe leading from within the heater chamber into the mixing chamber, and a plurality of pipes in parallel within the heater chamber connecting the fuel supply pipe and the gas delivery pipe.

2. A gas generator for an internal combustion engine comprising an elongate casing adapted to be secured along the side of an engine, the casing having a heating chamber communicating directly with the exhaust ducts of the engine, a mixing chamber in the casing, a fuel duct extending through said heating chamber and leading into said mixing chamber, all of the wall area of the fuel ducts being exposed to the heat in the 130

heating chamber, and a mixture delivery duct leading from the mixing chamber through the heating chamber to the engine.

3. A gas generator for an internal combustion engine comprising an elongate casing adapted to be secured along the side of an engine, the casing having a heating chamber communicating directly with the exhaust ducts of the engine, a mixing chamber in the casing, a branched fuel duct extending longitudinally through said heating chamber and leading into said mixing chamber and exposed on all sides to the heat in the heating chamber, and a mixture delivery duct leading from the mixing chamber through the heating chamber to the engine.

4. A gas generator for an internal combustion engine comprising a casing adapted to be secured along the side of an engine, the casing having an elongate heating chamber communicating directly with the exhaust ducts of the engine, a branched fuel duct extending longitudinally through said heating chamber, a second branched fuel duct extending longitudinally through said heating chamber, the second fuel duct having a cross-sectional area larger than that of the first fuel duct, and means for feeding fuel through the first fuel duct, thence through the second fuel duct and thence to the engine.

5. A gas generator for an internal combustion engine comprising a casing adapted to be secured along the side of an engine, the casing having an elongate heating chamber communicating directly with the exhaust ducts of the engine, a branched fuel duct extending longitudinally through said heating chamber, the fuel duct increasing in cross-sectional area intermediate its ends so that fuel passing therethrough may expand as it is heated, and means for conducting fuel from said fuel duct to the engine.

6. A gas generator for an internal combustion engine comprising a casing adapted to be secured along the side of an engine, the casing having an elongate heating chamber communicating directly with the ex-

haust ducts of the engine, a mixing chamber in the casing at one side of the heating chamber, a fuel duct extending longitudinally through the heating chamber to the mixing chamber, and means for conducting fuel from the fuel duct to the engine.

7. A gas generator for an internal combustion engine comprising a casing adapted to be secured along the side of an engine, the casing having an elongate heating chamber communicating directly with the exhaust ducts of the engine, an auxiliary heating chamber disposed along one side of the elongate heating chamber, the auxiliary heating chamber communicating with the elongate heating chamber at one end and having an exhaust outlet at the other end, a mixing chamber in said casing adjacent the auxiliary heating chamber, a fuel duct passing longitudinally through the elongate heating chamber and leading into the mixing chamber, and a fuel delivery duct leading from the mixing chamber through the elongate heating chamber to the engine.

8. A gas generator for an internal combustion engine comprising a casing adapted to be secured along the side of an engine, the casing having an elongate heating chamber communicating directly with the exhaust ducts of the engine, an auxiliary heating chamber disposed along one side of the elongate heating chamber, the auxiliary heating chamber communicating with the elongate heating chamber at one end and having an exhaust outlet at the other end, a mixing chamber disposed in an extension of said casing adjacent the auxiliary heating chamber, a branched fuel duct extending longitudinally through the elongate heating chamber and communicating with the mixing chamber, the fuel duct increasing in cross-sectional area intermediate its ends, and a mixture delivery duct leading from the mixing chamber through the heating chambers to the engine.

Signed by me at Farmington, Maine, this 28th day of July, 1916.

FRED D. JORDAN.
